Joseph A. Gibson, Kimball, Nebr.

Application January 19, 1948, Serial No. 3,140

5 Claims. (Cl. 312—233)

1

This invention relates to a rack for supporting flexibly-bound catalogues, or pamphlets, or sheets. It is necessary in mercantile establishments to have a multiplicity of catalogues and price sheets of the various articles of merchandise. It is desirable to have these catalogues and sheets supported in a manner permitting convenient and ready reference.

The principal object of this invention is to provide a rack which will support one or more binders containing catalogues, pamphlets, or sheets, in such a manner that any desired binder may be drawn from the rack to a free, accessible, and flat open position, with a moderate convenient tilt toward the operator.

Another object of the invention is to so construct the device that any desired catalogue, pamphlet, or sheet, may be quickly and easily detached from or replaced in the binder.

A further object of the invention is to so construct the device that any desired binder may be quickly and easily detached from or replaced in the rack so that the binders will be readily portable.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a plan view of the improved catalogues volume holder;

Fig. 2 is a detail cross-section, taken on the line 2—2, Fig. 1;

Fig. 3 is a longitudinal section, taken on the line 3—3, Fig. 1;

Fig. 4 is a front view of the improved holder; and

Fig. 5 is a bottom view of a back plate employed in the improved holder.

The holder comprises an open, box-like frame consisting of a bottom board 10, a back board 11, and two end boards 12. The front and the top of the frame are open. A plurality of volume separators 13 extend horizontally forward from the back board 11 in parallel relation. The frame may be of any length to contain any desired number of volumes. As illustrated, it is designed to support three volumes, indicated in broken line at 14, 15, and 16.

The volumes are provided with two relative stiff covers as indicated in broken line, punched with round holes along the inner, or binding edge. The catalogues, pamphlets, or sheets to be supported in the volumes, are punched with

2

holes along the binding edge. Binding rods 17 pass completely through the covers, catalogues, pamphlets and sheets. The binding rods extend through an elongated, channel-shaped backing plate 18 of sufficient width to receive the back of the volumes. One extremity of each binding rod 17 is turned to form an L-shape, and the turned extremity is bent back upon itself to form an open handle portion 19. A holding clip 20 is attached to the side of the plate 18 below each handle 19 to receive the latter and maintain it in its inserted horizontal position.

A slide 21 is riveted or otherwise secured along, and extends longitudinally of, the bottom of the plate 18 throughout its entire length. One extremity of the slide 21 projects beyond the plate 18 and is turned upwardly to form a pull hook 22. The side edges of the slide 21 are spaced downwardly from the plate 18 in parallel relation so that they may travel into a channeled guide member 23 having inwardly turned edges which slidably engage the side edges of the slide.

The guide member 23 is provided with a stop slot 24, one side of which is indented and the other side of which is raised to form an abutment for a latch pin 25. The latch pin is mounted in a bracket 26 which is hingedly mounted on the top of the rear extremity of the plate 18 by means of hinge hooks which engage in hook openings in the plate 18. The weight of the bracket 26 and the pin 25 force the latter downwardly so that when the plate 18 is pulled outwardly on the guide 23, the pin will engage the abutment formed by the slot 24 to limit the outward movement of the plate 18. The plate 18 can be completely removed from the guide 23 by simply lifting the hinged bracket 26 upwardly sufficiently to release the latch 25 from the slot 24.

The guide member 23 is telescopically received in a similarly shaped and slightly larger guide track 27 having similar inwardly turned edges which slidably receive the side edges of the guide member 23. The longitudinal movement of the guide member 23 in the track 27 is limited by a stop pin 28 which extends downward and travels in an elongated slot 29 in the track 27. The track 27 is fixedly mounted on an inverted, U-shaped hinge bracket 30 having downwardly turned bearing ears through which a hinge pin 31 passes. The hinge pin is supported in pin clips 32 secured to the base board 10 by means of suitable screws.

When not in use, the volumes are slid between the volume separators 13 which support them in the upright position of Fig. 4. Access may be had to any volume by simply pulling it from the frame, causing the guide member 23 to travel outwardly in the guide member 23 until the latch pin 25 engages the abutment of the stop slot 24. The plate 18 is then lowered to the surface of the

counter or supporting table, the hinge bracket 30 tilting upon the hinge pin 31 as shown in Fig. 3. The volume can now be laid out open on the table without interference from the other volumes. It is returned by simply closing the volume and pushing it toward the receiving frame so that the members 21, 23, and 27 automatically telescope together.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A holder or binder for supporting catalogues, pamphlets or sheets, comprising: a channel-shaped back plate adapted to extend across the back of catalogues, pamphlets, or sheets, and upwardly at each side of said back; binding pins extending through the catalogues, pamphlets, or sheets, between the upstanding sides of said back plate, for locking them therein; a slide member secured to and below the back plate and extending longitudinally thereof, the side edges of said slide member being spaced from, and in parallel relation to, the lower surface of said back plate; a guide member having upwardly and inwardly turned edges telescopically receiving the side edges of said slide member; a track member similar in construction to said guide member and having upwardly and inwardly turned side edges slidably receiving said guide member; a hinge secured to and below said track member upon which said track member may be tilted; and means for mounting said hinge on a supporting surface.

2. A holder for supporting loose-leaf volumes, comprising: a channel-shaped back plate adapted to extend across the back of a volume and upwardly at each side of said back; binding pins extending through the volume between the upstanding sides of said back plate for locking the pages therein; a slide member secured to and below the back plate and extending longitudinally thereof, the side edges of said slide member being spaced from, and in parallel relation to, the lower surface of said back plate; a guide member having upwardly and inwardly turned edges telescopically receiving the side edges of said slide member; a track member similar in construction to said guide member and having upwardly and inwardly turned side edges slidably receiving said guide member; a hinge secured below said track upon which said track member may be tilted; means for mounting said hinge on a supporting surface; and means for limiting the longitudinal movement of said guide in said track member.

3. A holder for supporting loose-leaf volumes, comprising: a channel-shaped back plate adapted to extend across the back of a volume and upwardly at each side of said back; binding pins extending through the volume between the upstanding sides of said back plate for locking the pages therein; a slide member secured to and below the back plate and extending longitudinally thereof, the side edges of said slide member being spaced from, and in parallel relation to, the lower surface of said back plate; a guide member having upwardly and inwardly turned edges telescopically receiving the side edges of said slide

member; a track member similar in construction to said guide member and having upwardly and inwardly turned side edges slidably receiving said guide member; a hinge secured below said track upon which said track member may be tilted; means for mounting said hinge on a supporting surface; means for limiting the longitudinal movement of said guide in said track member; a hinged bracket member mounted on and projecting rearwardly from said back plate; a latch pin extending downward from said bracket member against said guide member; and means on said guide member to be engaged by said pin to limit the outward movement of said back plate on said guide member.

4. A holder for supporting loose-leaf volumes, comprising: a channel-shaped back plate adapted to extend across the back of a volume and upwardly at each side of said back; binding pins extending through the volume between the upstanding sides of said back plate for locking the pages therein; a slide member secured to and below the back plate and extending longitudinally thereof, the side edges of said slide member being spaced from, and in parallel relation to, the lower surface of said back plate; a guide member having upwardly and inwardly turned edges telescopically receiving the side edges of said slide member; a track member similar in construction to said guide member and having upwardly and inwardly turned side edges slidably receiving said guide member; a hinge secured below said track upon which said track member may be tilted; a bottom board; means for securing said hinge to said bottom board; a back board projecting upwardly from said bottom board at the rear of said track; and means extending forwardly from said back board for supporting the sides of said volume when not in use.

5. A holder for supporting loose-leaf volumes, comprising: a channel-shaped back plate adapted to extend across the back of a volume and upwardly at each side of said back; binding pins extending through the volume between the upstanding sides of said back plate for locking the pages therein; a slide member secured to and below the back plate and extending longitudinally thereof, the side edges of said slide member being spaced from, and in parallel relation to, the lower surface of said back plate; a guide member having upwardly and inwardly turned edges telescopically receiving the side edges of said slide member; a track member similar in construction to said guide member and having upwardly and inwardly turned side edges slidably receiving said guide member; a hinge secured below said track upon which said track member may be tilted; means for mounting said hinge on a supporting surface, said slide projecting forwardly from said back plate; and an upwardly turned hook formed on the forward extremity of said slide.
